UNITED STATES PATENT OFFICE.

JAMES WOOD, OF PITTSBURG, PENNSYLVANIA.

DESIGN FOR THE ORNAMENTATION OF SHEET METAL.

SPECIFICATION forming part of Design No. 17,621, dated August 9, 1887,

Application filed March 2, 1887. Serial No. 229,485. Term of patent 14 years.

To all whom it may concern:

Be it known that I, JAMES WOOD, of Pittsburgh, in the county of Allegheny and State of Pennsylvania, have invented a new and useful 5 Design for the Ornamentation of Sheet Metal; and I do hereby declare the following to be a full, clear, and exact description thereof.

In the accompanying drawings, Figure 1 shows in plan view a piece of sheet metal ornamented with the design, and Fig. 2 is a vertical cross-section on the line $x x$ of Fig. 1.

Like symbols of reference indicate like parts in each.

As shown in the drawings, the sheet metal 15 is ornamented with the well-known hammer-mark pattern—*i. e.*, with a series of contiguous curved or polygonal bosses or figures in relief. The sheet is provided on the hammer-mark pattern with spots $b b$. A distinctive 20 appearance is thus produced.

I do not claim, broadly, as a design sheet

metal ornamented with the hammer-mark pattern, for that is old; nor do I claim, broadly, as a design sheet metal whose surface is ornamented with spots. The leading and distinguishing feature of the design consists in the hammer-marked sheet metal provided with spots $b b$. 25

I claim—

The design for the ornamentation of sheet 30 metal, consisting in a metal sheet ornamented with a series of contiguous bosses or figures in relief, constituting a hammer-mark pattern, and having spots $b b$ on said pattern, as herein shown and described. 35

In testimony whereof I have hereunto set my hand this 21st day of February, A. D. 1887.

JAMES WOOD.
